Attorney, Agent, or Firm—Cushman, Darby & Cushman

[57] **CLAIM**

The ornamental design for an upper surface decoration for a plate or similar article, as shown and described.

DESCRIPTION

The FIGURE is a plan view of an upper surface decoration for a plate or similar article showing my new design;

The broken line about the FIGURE is illustrative of the environmental structure of a plate. The stippled shading represents shading of color variations and not changes of surface contours.
